INTERNAL COMBUSTION ENGINE

Arthur Alexander Sidney, Thornton Heath, England, assignor to Bryce Limited, a company of Great Britain

Application March 31, 1932, Serial No. 602,339
In Great Britain April 2, 1931

2 Claims. (Cl. 299—107.1)

This invention relates to internal combustion engines of the kind in which a combustible charge of petrol or other volatile fuel is ignited in a combustion chamber or engine cylinder by means 5 of a sparking or like device.

The invention has for its object to provide an internal combustion engine of the above type which is also adapted to operate on heavy or non-volatile oil, such for example as is used for Diesel 10 engines.

According to the invention means is provided for introducing either volatile or non-volatile fuel oil in a substantially or at least partially atomized form into the cylinder or combustion chamber of 15 an internal combustion engine prior to the induction stroke of the piston and the mixture of fuel and air is subsequently ignited by means such as an electric spark.

The fuel oil may be delivered through an injector device to the cylinder by means of a pump 20 (such for example as is commonly used for Diesel type engines).

Means may be provided for controlling the quantity of air aspirated by the engine and such 25 means may be controlled in accordance with the supply of fuel.

Further features of the invention will be hereinafter described or indicated.

In the accompanying drawing:—

30 Fig. 1 is a diagrammatic view showing an internal combustion engine to which the present invention is applied; and

35 Fig. 2 is a sectional view illustrating a fuel injection nozzle constructed according to the present invention.

In carrying the invention into effect in one convenient manner and as illustrated in the drawing, a cylinder 1 of a petrol or like low compression internal combustion engine is provided with a 40 sprayer or injector 2, which latter is connected to a fuel pump 4 as through a pipe 3, the said pump being preferably driven from the engine.

A valve 5 having an operating lever 6 controls the volume of air which is aspirated by the engine through an induction pipe 7. The said operating lever 6 is connected as by a link 8 to a control lever 9 of the fuel pump, operation of said lever 9 serving to regulate the quantity of fuel delivered by the pump, the arrangement being 45 preferably such that adjustment of the pump, so as to vary the delivery of fuel and thereby to vary the output of the engine, is accompanied by a corresponding adjustment of the position of the air valve 5 and consequently adjustment of the 50 quantity of air aspirated by the engine. It is

thus possible to maintain a uniform ratio of fuel to air for all values of the engine output.

Referring to Fig. 2, the sprayer or injector comprises a body 10 adapted to be inserted through an aperture in the wall of an engine cylinder or cylinder head and may be screw-threaded for this purpose preferably with the same thread as that which is employed for standard sparking plugs. The body 10 of the sprayer or injector has a bore 11 terminating in an orifice 12 which latter is partially closed by the tapered portion 13 of a needle valve 14. An extension 15 of the valve 14 carries a deflector 16 which is provided with an annular deflecting surface 17 and the body 10 is formed with two sleeves 18 and 19 which enclose 10 between them a further annular deflecting surface 20, the outer sleeve 18 being extended and a gap 21 being left between the edge of such extension and the edge of the deflector 16.

In the operation of this sprayer or injector a 20 jet of fuel oil issues through a small annular clearance separating the tapered portion 13 of the valve 14 and the aperture 12. Part of such jet of fuel is immediately atomized and passes immediately away from the sprayer through the gap 21. 25 The denser particles of the fuel jet, however, impinge upon the deflecting surface 17 and as a consequence of this, the denser particles of fuel have their motion reversed and are directed onto the inner part of the surface 20. This latter surface 30 again reverses the direction of motion of such particles of fuel and redirects same such that they may issue through the gap 21.

The atomization of the fuel jet is completed by 35 impact thereof against the said surfaces and by the heat which it receives therefrom, these surfaces, and particularly the surfaces 17, being heated by the explosions that occur in the engine cylinder.

Any suitable form of fuel pump or air valve 40 may be employed with the invention but in the case of the former it is preferred to employ a fuel pump such as is described in either of the co-pending British applications Nos. 1732 of 1932 or 1812 of 1932, and which has the advantage of being capable of operation at high speeds and of dealing with petrol or like liquids having little or no lubricating qualities.

No change is made in the normal ignition or valve timing or in the other arrangements of the 50 engine, but the carburettor is preferably dispensed with.

It is well known that heavy fuel oil may be employed in compression ignition engines and that 55 on account of the low cost of this oil as compared

with petrol, power may thus be very economically obtained. Such engines, however, as compared with petrol engines, have the disadvantages of increased weight, and roughness of running, because of their high compression ratio and are limited in speed. An engine adapted according to the present invention to use heavy oil retains the characteristics of the low compression petrol engine, these being, lightness, smoothness of running and high speed and has, at the same time, the advantage of using a cheap fuel.

It is to be understood that the invention is not limited to the above details except in the manner set forth.

15 I claim:

1. A fuel injection nozzle for an internal combustion engine comprising a body portion, an internal surface defining an orifice in said body portion, a concavely curved deflecting surface surrounding said orifice, a sleeve portion surrounding said deflecting surface, and an additional deflector located so as to lie across the path of fluid issuing from the orifice and having an annular deflecting surface concavely curved to said ad-

ditional deflector, the deflecting surfaces on said body portion and said additional deflector facing each other in such a manner that fluid issuing from the nozzle is deflected by said deflector back onto the body and thence through the space between the deflector and sleeve.

2. A fuel injection nozzle for an internal combustion engine comprising a body portion, an internal surface defining an orifice in said body portion, a concavely curved deflecting surface surrounding said orifice, a sleeve portion surrounding said deflecting surface, a needle valve adjusting the size of said orifice, an extension to said needle valve extending beyond said sleeve, and a deflecting disc carried on the end of said needle valve extension in spaced relationship with the edge of said sleeve and having an annular concavely curved deflecting surface thereon, the deflecting surfaces on said body and said disc facing each other so that fluid issuing from the orifice is deflected by the disc back onto the surface surrounding the orifice and thence through the space between the sleeve and the disc.

ARTHUR ALEXANDER SIDNEY.
